UNITED STATES PATENT OFFICE

HERBERT S. HUMPHREY, OF KALAMAZOO, MICHIGAN, ASSIGNOR TO H. L. G. COMPANY, OF KALAMAZOO, MICHIGAN

DESIGN FOR A VALVE CASING

Application filed December 27, 1932. Serial No. 46,628. Term of patent 7 years.

To all whom it may concern:

Be it known that I, HERBERT S. HUMPHREY, a citizen of the United States, residing in the city and county of Kalamazoo, State of Michigan, have invented a new, original, and ornamental Design for a Valve Casing, of which the following is a specification, reference being had to the accompanying drawing, forming part therof.

The figure is a side elevational view of a valve casing, showing my new design.

I claim:

The ornamental design for a valve casing, as shown.

HERBERT S. HUMPHREY.
